(57) CLAIM

We claim the ornamental design for a cosmetic brush cleaning pad, as shown and described.

DESCRIPTION

FIG. 1 is a perspective view of an aspect of the cosmetic brush cleaning pad.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

Those features shown in broken lines, including a base comprising a wavy flange, as shown in FIGS. 1-7, form no part of the claimed design.

1 Claim, 5 Drawing Sheets(56)
